[57] CLAIM

The ornamental design for a cushion, as shown and described.

DESCRIPTION

FIG. 1 is a perspective view of a cushion showing my new design;

FIG. 2 is a top plan view of the cushion;

FIG. 3 is a bottom plan view of the cushion;

FIG. 4 is a side elevational view of the cushion;
FIG. 5 is another side elevational view of the cushion, taken approximately 90 degrees from the view shown in FIG. 4; and

FIG. 6 is a side sectional view of the cushion taken along line 6—6 of FIG. 4 in the direction of the arrows.

*Fig. 1.**Fig. 2.**Fig. 3.**Fig. 4.**Fig. 5.**Fig. 6.*
